H. E. THOMPSON

PERMANENT FOUNDATION FOR PAINTINGS

Filed Oct. 22, 1923

Inventor:

Herbert E. Thompson,

By Bruce Townsend & Brickerstein,
Attorneys.

UNITED STATES PATENT OFFICE.

HERBERT E. THOMPSON, OF WALTHAM, MASSACHUSETTS.

PERMANENT FOUNDATION FOR PAINTINGS.

Application filed October 22, 1923. Serial No. 670,153.

To all whom it may concern:

Be it known that I, HERBERT E. THOMPSON, a citizen of the United States, residing at 780 Lexington St., Waltham, in the county of Middlesex and State of Massachusetts, have invented certain new and useful Improvements in Permanent Foundations for Paintings, of which the following is a specification.

10 This invention relates to the fine arts and particularly to permanent and unalterable foundations for paintings.

While not limited in its application thereto, my invention is particularly adapted for 15 use as a permanent foundation for old paintings and masterpieces having canvas or wood foundations which have deteriorated or have been destroyed by age. According to present practices, the defective foundations of such paintings are carefully removed from the rear of the painting which is then mounted upon a new canvas. Obviously this expedient offers only a temporary relief, since the new canvas foundation is affected and will in time be destroyed by moisture and the other influences which destroyed the original canvas.

An object of the invention is to provide 20 a permanent foundation for paintings which will not be affected by moisture and which will not deteriorate with age. More specifically an object of the invention is to provide a permanent foundation comprising a metal plate having a coating fixed thereto and upon which oil or water colors 25 may be painted or to which a previously prepared painting may be transferred.

Embodiments of my invention are illustrated in the accompanying drawings, in 30 which,

Fig. 1 is an elevation, partly in section, of a permanent foundation embodying my invention;

Fig. 2 is an enlarged horizontal section of the foundation as taken on line 2—2 of Fig. 1;

Fig. 3 is a fragmentary section similar to Fig. 2 but greatly enlarged;

Fig. 4 is an elevation, partly in section 50 of a modified construction, and

Fig. 5 is a fragmentary horizontal section illustrating a further modification.

In the drawing, the numeral 1 designates the metal plate which provides the necessary backing for the picture receiving surface 2. While various metals and alloys,

such as copper, zinc or a ferro-nickel alloy such as invar may be used, I prefer to use aluminum as this metal is lighter than the other metals or alloys and possesses the same 60 resistance to corrosion. The surface coating 2 is preferably of gesso, a composition of glue or size, whiting and oil.

To form a permanent union, the metal backing 1 and the coating 2 are mechanically 65 interlocked by means of undercut projections 3 which are formed on the surface of the plate with a pointed tool. To further increase the adhesion, the burred plate 1 is given a coat 4 of varnish, preferably 70 a lac varnish which is allowed to harden before the gesso is applied. The gesso coating may be applied by hand or by machine according to known methods of applying 75 smooth plastic coatings.

If desired, the metal plate 1 may be etched by a sand blast or acid as indicated at 5 in Fig. 4, either before or after the projections 3 are formed on the plate. When so etched, the adhesion between the plate 80 and the varnish coating 4 is increased. In the modification shown in Fig. 5, the interlocking of the plate and the gesso coating is secured by undercut recesses 6, but no 85 burrs project above the surface of the plate as in the form shown in Figs. 2 and 3. When a plate of this type is employed a thinner layer of the gesso may be used.

A coated metal panel or permanent foundation such as described may be painted 90 upon with oil or water colors in the usual way or the coated metal panel may be used as a permanent backing for previously prepared paintings. If the canvas or other foundation of a painting is in good 95 condition, the painting may be mounted on the coated metal plate by cementing or fixing the canvas to the gesso surface with suitable adhesives. Ordinarily, however, a painting will be given a new foundation 100 only when the original foundation is defective. In such cases the canvas or other foundation is carefully abraded and picked from the rear of the picture until only the paint film remains. The paint film may 105 then be transferred and fixed to the permanent coated metal panel by the use of materials and processes which are now employed in transferring a painting to a canvas foundation.

110 It will be apparent that the invention is not limited to the specific embodiments

herein described, since various changes may be made in the construction without departing from the spirit of my invention, one such change, for example, being the use of 5 haphazard projections on the plate instead of the alined projections which are shown in the drawings.

I claim:

1. A permanent foundation for paintings 10 comprising a metal plate and a coating of gesso adapted to receive a painting, said metal plate and coating being mechanically interlocked.
2. A permanent foundation for paintings 15 comprising a metal plate having undercut recesses on one face thereof, and a coating of gesso adapted to receive a painting mechanically interlocked to said plate by said undercut recesses.
3. A permanent foundation for paintings,

comprising a metal plate having undercut recesses on one face thereof, a coating of varnish on said recessed face, and a coating of gesso adapted to receive a painting over said varnish coating and mechanically interlocked to said plate by said undercut recesses. 25

4. A permanent foundation for paintings, comprising an aluminum plate and a coating of gesso mechanically interlocked to 30 said plate.

5. A permanent foundation for paintings, comprising an aluminum plate having recesses on one face thereof, a coating of varnish on said recessed face and a coating of 35 gesso mechanically interlocked to said plate by said recesses.

In testimony whereof, I affix my signature.

HERBERT E. THOMPSON.
